[57] **CLAIM**

The ornamental design for a strip cutter, substantially as shown and described.

DESCRIPTION

FIG. 1 is an isometric view showing the top one end and one side of the strip cutter showing my new design; FIG. 2 is an opposite side elevational view thereof; FIG. 3 is a bottom plan view thereof; and FIG. 4 is an opposite end elevational view thereof. The cross member is adjustable along the elongated guide rail.
